UNITED STATES PATENT OFFICE.

EDWARD H. JUNGCLAS, OF CINCINNATI, OHIO.

MILK-BOTTLE PITCHER ATTACHMENT.

1,027,421.

Specification of Letters Patent.

Patented May 28, 1912.

Application filed August 22, 1911. Serial No. 645,439.

To all whom it may concern:

Be it known that I, EDWARD H. JUNGCLAS, a citizen of the United States of America, and resident of Cincinnati, county of 5 Hamilton, and State of Ohio, have invented certain new and useful Improvements in Milk-Bottle Pitcher Attachments, of which the following is a specification.

My invention relates to improvements in 10 milk bottle pitcher attachments, and has for an object to produce a pitcher attachment which may be quickly and securely attached to an ordinary milk bottle.

Another object is to produce a milk bottle 15 pitcher attachment wherein means are provided for removing and replacing the paper stopper of the bottle, as often as desired.

A further object of my invention is to 20 produce a milk bottle pitcher attachment wherein means are provided for hermetically sealing the bottle, after its contents have been partially removed.

These and other objects are attained by 25 the means described in the following specification, and illustrated in the accompanying drawing, in which—

Figure 1 is a side elevation of an attachment, embodying my invention, parts thereof 30 of being shown broken away. Fig. 2 is a perspective view of a stopper remover.

The attachment comprises a body portion 1, a hinged lid 2, and a disk remover 3. The body portion comprises a circular ring and 35 a spout. The ring is of a diameter intermediate in size between the external diameter of the mouth of a milk bottle of standard size and the internal diameter thereof.

Integrally formed with the body portion 40 and extending downwardly from the circular lower part, is an annular series of springs 4, adapted to engage the rim 5 of the bottle neck. From the inner wall of the body portion, and located above the 45 springs, is an internal annular ring 6, against which rests a packing ring 7. Hinged to the body portion, by means of spring-hinge-joint 9, is the lid 2, which is adapted to close the mouth opening of the 50 body portion 1. The lid is provided with a thumb piece 18, for raising it conveniently. In the lid is an opening 11, so located as to register with the center of the bottle opening. Opening 11 is surrounded 55 with a reinforcing lug. Within opening 11,

and adapted to reciprocate therein, is a paper-stopper or disk remover, comprising a plate 13, a spindle 14, and a winged-handle 15. Projecting from the underside of plate 13 are pointed hooks 16, which are 60 adapted to be engaged with the paper bottle stopper 17, in order to remove it.

In using my attachment, it is forced over the mouth of a fresh and unopened bottle, springs 4 expanding to permit this. The 65 attachment is forced down tight upon the bottle, so that the packing ring 7 is caused to contact the edge of the bottle, to prevent leakage of the bottle's contents between the attachment and the bottle. The ring is 70 maintained in this position by springs 4. The stopper remover is forced downward upon the paper bottle stopper, and winged-handle 15 is turned to embed the pointed hooks in the stopper. The stopper may be 75 removed from the bottle by an upward pull. The paper stopper may be reinserted within the bottle opening, by pushing down upon the disk remover, thus affording a positive 80 air tight closure for the bottle, after partially removing its contents.

What I claim is:—

1. A bottle attachment of the character described, comprising a spout, depending springs integrally formed on said spout for removably securing the spout on the top of a bottle, a lid for said spout and a bottle-stopper remover mounted on said lid. 85

2. In a bottle attachment, the combination of a ring, means for attaching it to a 90 bottle, a lid hinged to the ring, and a bottle-stopper remover consisting of a rod mounted reciprocally in the lid, and carrying at its lower end tangs for engaging the stopper. 95

3. In an attachment for bottles of the character described, the combination of, a pouring spout means for removably mounting the spout on the bottle, a lid for closing the spout, and a bottle-stopper remover 100 movably mounted on the lid.

4. A bottle attachment of the character described, comprising a ring, means for removably attaching the ring to the bottle, a lid hinged to the ring, and a bottle-stopper remover movably mounted on said lid. 105

5. A bottle attachment of the character described, comprising a pouring spout, a lid hinged on said spout, and a bottle-stopper remover consisting of a rod, mount- 110

ed reciprocally in the lid, and carrying at its lower end tangs for engaging the stopper.

6. A bottle attachment of the character described comprising a ring, means for removably mounting the ring on the top of a bottle, a brace mounted on the ring, extending longitudinally of the bottle and

engaging a lateral face thereof, a spout formed on the ring a lid for closing the spout 10 and a bottle-stopper remover mounted on said lid.

EDWARD H. JUNGCLAS.
